(57) CLAIM

The ornamental design for an umbrella clip, as shown and described.

DESCRIPTION

FIG. 1 is a bottom plan view of the umbrella clip, showing my new design;

FIG. 2 is a top plan view thereof;

FIG. 3 is a left side elevational view thereof;

FIG. 4 is a back elevational view thereof;

FIG. 5 is a front elevational view thereof; and,

FIG. 6 is a right side elevational view thereof.

The broken lines shown in the figures are for the purpose of illustrating portions of the umbrella clip and form no part of the claimed design.

1 Claim, 1 Drawing Sheet
